EYE BLOCK FOR SHUTTLES

Carl Palmer Park, Manchester, N. H., assignor to
U S Bobbin & Shuttle Company 1929, Providence, R. I., a corporation of Rhode Island

Application October 30, 1935, Serial No. 47,455

6 Claims. (Cl. 139—222)

This invention relates to shuttles, particularly of the hand threading type, and is substantially a one piece shuttle eye block which takes the place of a tubular, transverse, horizontal, porcelain or metal eye, and of the vertical outlet pin or pins of porcelain or metal now in common use with such shuttles.

Its principal advantages are that there are no pins or other parts which can come out and cut the warp, and that it can be made of one piece of porcelain, hard steel, stainless steel, chromium plated metal such as brass, agate, glass or any material which will stand the wear of the thread as it is swiftly running out through the shuttle eye from the bobbin.

Other advantages are that the wood of the shuttle adjoining this eye block can be easily and cheaply cut without too much weakening of the shuttle and the block can be inserted in place from the top of the shuttle, locked in place by means which are sealed up, so that there is a perfectly smooth surface at the top of the block recess, but the filling is of such nature that if the eye block gets worn, chipped or broken, it can easily be removed and replaced by another one.

The block and the recess are so made that the block can readily be slid or pressed into position, but the front, back and bottom of the recess are so made that the block can not move nor get out of position.

The eye block is so made and placed that the thread can be quickly brought down through a threading slot and then through an eye inlet slot in the wood, in through the mouth or opening at the front of an eye inlet in the block which preferably extends down and then up into the bottom of a transverse eye passage, the wood being so cut that while the thread can readily get into the eye, it cannot readily get out of the eye.

All parts of the block which the thread touches are smooth, hard and curved, and except when threading, the thread touches no part of the wood except along the usual thread groove in the side of the shuttle, whereby catching, wearing and shinners are avoided.

In the drawings, Fig. 1 is a plan view of the eye end of a shuttle with the preferred form of the device in place.

Fig. 2 is an elevation of Fig. 1 from the eye side.

Fig. 3 is a vertical section as on line 3—3 of Fig. 1.

Fig. 4 is a view similar to Fig. 3 but with the plastic wood filling and eye block removed.

Fig. 5 is a vertical section on the line 5—5 of Fig. 3.

Fig. 6 is a vertical section on the line 6—6 of Fig. 3.

Fig. 7 is a horizontal section looking down on the line 7—7 of Fig. 2.

Fig. 8 is a plan view similar to Fig. 1 of a shuttle without a friction device.

Fig. 9 is a view similar to Fig. 3 of a slightly different eye block held in place in a slightly different way, but without the filling in the top part of the block recess.

Fig. 10 is a view similar to Fig. 9 of another modification.

Fig. 11 is a view similar to Fig. 9 of still another modification.

Fig. 12 is an elevation similar to Fig. 2 showing a shuttle cut in a slightly different manner.

Fig. 13 is a view similar to Fig. 3 of another modification of the eye block.

Fig. 14 is an enlarged sectional view of the construction shown in Fig. 8 on a horizontal plane in a similar position to 7—7 in Fig. 2.

Fig. 15 is a view similar to Fig. 14, showing a modification of the eye block.

In the drawings, S represents a shuttle with the usual point 99, bobbin chamber 1 and threading slot 2 in forward extension thereof. As shown, A represents a metal friction device in which is a thread pin member 7 about which the thread 30 such as T turns after it is threaded and passes out through an eye in the side 98.

9 represents the top of the shuttle and 5 is the usual thread groove along the side, while 3 is an inlet slot which connects the threading slot 2 with 35 an eye hole 4 through the wood in the side of the shuttle and connects also with thread groove 5. 6 is a depression forming part of thread groove 5 in alignment with inlet slot 3 and which tapers down to a thin edge where it adjoins the eye block B and the transverse passage 14 therein.

8 is an eye block recess which extends down from the top 9 of the shuttle and B is the threading block which is curved at its front 12 and back 17 to fit recess 8, and is flat at its back bottom part 11 to rest on the flat bottom of recess 8, while its height is such that when pushed down in place, there is a space above it which is preferably filled with plastic wood or similar material.

Preferably also it is held in place as by a staple such as 10 which is slipped down onto the top 19 of block B and then pressed in horizontally and backwardly as shown in Fig. 3. Any of the devices shown in Figs. 9, 10 and 11 might be used, 55

however. The plastic wood P is then pressed in place to leave a smooth top.

14 is the transverse eye passage through block B positioned in alignment with eye hole 4 and eye groove 5 and particularly the part 6. There is an inlet 15 in the bottom of eye passage 14, and in front of the vertical wall 16, which extends down below and then up at the mouth 13 above the bottom of the eye inlet slot 3 in the wood.

10 As shown in Fig. 7, the wood is so cut that there is enough space around the bottom front of the eye block B to allow the thread to go down from the eye inlet slot in the wood into the eye passage 14 and eye hole 4 which together form the 15 shuttle eye.

A convenient way to make an eye 4 and to leave space enough around mouth 13 is to bore a transverse hole 104 in the wood and then block part of it up at R.

20 As shown in Fig. 8, in a hand threading shuttle, there can be cut a threading slot 22 in which there is no metal friction such as A, but in which there is a thread pin 27 in the angle between the threading slot 22 and the eye inlet slot 23. Block B and the other parts of the wood 25 are the same as in Fig. 1.

The shapes of the eye block and the methods of locking it in place to prevent vertical displacement, are shown in Figs. 9, 10, and 11.

30 In Fig. 9, the block F has the bottom 31 which is wider than the bottom 11 of B, while the mouth 33 at the front 32 is not as high. The front wall 32 and back wall 37 are rounded, as are also the walls of the inlet 35 for transverse passage 34, while the top 38 of the mouth 33 slopes upward and the block is held in place by a strip 30 held down by a screw 29, the top part 88 of the block recess being lengthened out toward the back to accommodate them.

40 In Fig. 10, G shows another modification of the eye block with a curved front wall 42 and back wall 47, flat top 49 and bottom 41 from which extends upward the inlet passage 45 for transverse eye passage 44. The front part 48 of the bottom 45 41, which is an extension of the inlet 45, extends up and forward to form a mouth 43, while the block recess 148 is so cut that the back and front walls 47 and 42 and the rear part of the bottom 41 fit it, the bottom 141 keeping the block G in place. At the top is shown a locking device in the form of wire legs 40 which, when bent down as shown by the dotted lines, penetrate the wood, holding block G down in position.

50 In Fig. 11, the block recess can be the same as 55 8 while the block H has a curved front wall 52 and back wall 57, the bottom 51 extending from front to back the same distance as top 59, there being a transverse eye passage 54 with an inlet passage 35 which extends down under the 60 wall 58 and out at a mouth 53. Block H is held down and in position by the head of a screw 50, the top of the block recess being extended at 88, as it is also shown in Fig. 9.

In Figs. 12 and 13, the inlet slot 63 in the wood 65 goes down somewhat lower than in Fig. 1, and extends back horizontally as shown in Fig. 12, and then up at 64.

The block K has a horizontal inlet passage 60 which connects with or is formed as an inlet 61 70 for the transverse eye passage 62. The eye block inlet 61 coincides with the part 64 of inlet slot 63, while eye inlet 60 registers with inlet slot 63, its mouth 67 being above the bottom of 63.

The eye passage 62 in block K coincides with 75 a suitable eye hole 68 in the wood which registers

with a thread groove 66 in the side of the shuttle, 65 represents the block recess in which block K rests.

As shown in Figs. 8 and 14, I prefer to make the block recess such as 112 at a slight angle with the vertical plane through the axis of the shuttle whereby the front and back walls of the transverse eye passage, such as 14, or their edges 114 and 214 contract the passage and serve to retard the thread T as it runs through. Moreover, by making this recess at a slight angle with the vertical, and substantially parallel with the slope of the adjoining part of the shuttle, as shown in Fig. 8 and Fig. 14, the wood of the shuttle between the front of the block and the 15 side of the shuttle is weakened less than if it was parallel with the axis.

Block recess 112 must be enlarged at 204 to allow the thread to go around the front of block B into mouth 13 and passage 14. However, as 20 shown in Fig. 15, in place of such enlargement, the front 70 of an eye block M may be made narrower to leave room between M and the wall of block recess 71.

I claim:

1. The combination in a shuttle having an eye inlet slot which connects with an eye hole in the side of the shuttle, an eye block recess which extends at an angle with the shuttle axis and parallel with the slope of the adjoining part of the 30 shuttle down from the top to the eye inlet slot, and a thread pin member; of a one piece eye block positioned in the eye block recess and having a transverse eye passage at an angle between the eye hole and the thread pin, there being an inlet 35 at the bottom of the eye passage which extends down and thence forward and at its mouth above the bottom of the eye inlet slot, there being enough space around the bottom front and the outside of the eye block to allow the thread to 40 go from the eye inlet into the eye passage in the eye block.

2. The combination in a shuttle having a body in which is an eye inlet slot which connects with an eye hole and a thread recess in the side of the shuttle, an eye block recess which extends down from the top to the eye inlet slot and connects with the eye hole and thread recess, and a thread pin member; of a one-piece eye block positioned in the eye block recess and having a transverse cylindrical eye passage in alignment 50 with the eye hole, there being an inlet at the bottom of the eye passage which extends down and thence forward and which at its mouth is above the bottom of the eye inlet slot, there being 55 enough space around the bottom front of the eye block to allow the thread to go from the eye inlet into the eye passage in the eye block; means which extend over part of the eye block and penetrate the wood to hold it in position; and filling between the top of the eye block and the 60 top of the shuttle.

3. The combination in a shuttle having a main body in which is an eye inlet slot which connects with an eye hole in the side of the shuttle and an eye block recess which extends down from the top to the eye inlet slot; of a one piece eye block countersunk in the eye block recess and having substantially parallel vertical side walls and substantially parallel vertical front and back 70 walls, the distance between the side walls being less than between the front and the back walls, said eye block having a transverse cylindrical eye passage so positioned as to form part of the eye hole and with an inlet of less size and which en- 75

ters into the bottom of the eye passage; a passage from the eye block inlet to the shuttle body eye inlet slot; means which extend over part of the eye block and penetrate the main shuttle body to hold the eye block in position; and filling between the top of the eye block and the top of the shuttle.

4. A one piece eye block for shuttles having substantially parallel vertical flat side walls and substantially parallel vertical front and back walls, the distance between the side walls being less than between the front and back walls, said eye block having a transverse cylindrical eye passage and an inlet into such passage extending up from the bottom of the block and being of less size than the eye passage where it enters the eye passage, the lower part of the front wall being cut away so as to slope down and back to a point on said inlet which is above the bottom of the block.

5. The combination in a shuttle having a main body in which is a threading slot which connects with an eye inlet slot and an eye hole in the side of the shuttle and having an eye block recess which extends vertically in the shuttle so as to connect with the eye hole; of a one-piece eye block positioned in the eye block recess and having substantially vertical side, front and back

walls, the distance between the side walls being less than between the front and back walls and the vertical edges being rounded, said eye block having a transverse cylindrical eye passage with smoothly rounded edges, said eye block being so positioned that its eye passage forms part of the eye hole and having an inlet of less size than the eye passage, said inlet entering substantially at the bottom of the eye passage, the lower part of the front wall of the eye block sloping down to and connecting with the eye inlet at a point above the bottom of the eye block; and means to hold the eye block in the eye block recess.

6. A one-piece eye block for shuttles having substantially parallel vertical flat side walls and substantially parallel vertical front and back walls, the distance between the side walls being less than between the front and back walls, said eye block having a transverse cylindrical eye passage flaring outwardly and having smoothly rounded edges and an inlet into such passage extending up from the bottom of the block and being of less size than the eye passage where it enters the eye passage, the lower part of the front wall being cut away so as to slope down and back to a point on said inlet which is above the bottom of the block.

CARL PALMER PARK.
